COMBINED CHAIR AND TABLE UNIT

Franz Vogt, Pohlheim, Germany, assignor to Voko Franz
Vogt & Co., Pohlheim, Germany

Filed Feb. 19, 1974, Ser. No. 443,835

Claims priority, application Germany Aug. 17, 1973

Term of patent 14 years

Int. Cl. D6—05

U.S. Cl. D6—42

FIG. 1 is a perspective view of a combined chair and table unit embodying my new design;
FIG. 2 is a right side view thereof;
FIG. 3 is a front view thereof;
FIG. 4 is a top view thereof;
FIG. 5 is a bottom view thereof; and
FIG. 6 is a rear view thereof.

I claim:

The ornamental design for a combined chair and table unit, as shown.
